United States Patent

Des. 242,582
Patented Nov. 30, 1976

242,582

SIGN FOR GLASS DOORS OR THE LIKE

Jack Darrell, 1646 Old Spanish Trail,
Houston, Tex. 77054

Filed Sept. 17, 1975, Ser. No. 614,164

Term of patent 14 years

Int. Cl. D20—02

U.S. Cl. D96—12 G

The figure is a front elevation view of a sign for glass doors or the like showing my new design. The sign is of no substantial thickness.

I claim:

The ornamental design for a sign for glass doors or the like, as shown and described.
